INCENDIARY BOMB

Thomas P. Duncan, Jr., Newport News, Va.

Application March 16, 1942, Serial No. 434,943

3 Claims.

(Cl. 102—6)

This invention relates to an incendiary bomb, and it is an object of the invention to provide a device of this kind including a body of combustible material, together with means within the body made effective by an acid to allow dropping of the bomb at an approximate moment determined by both time and distance.

It is also an object of the invention to provide a bomb of this kind including a body of a highly combustible material, together with means for igniting the same by impact, and wherein such body is provided with means to effectively resist striking shock or impact, and thereby materially increasing the efficiency of the bomb.

An additional object of the invention is to provide a bomb of this kind provided with means for imposing drag or vane effect upon the bomb when dropping to insure the same traveling in desired effective course.

The invention consists in the details of construction and in the combination and arrangement of the several parts of my improved incendiary bomb whereby certain important advantages are attained, as will be hereinafter more fully set forth.

In order that my invention may be better understood, I will now proceed to describe the same with reference to the accompanying drawing, wherein:

Figure 1 is a longitudinal sectional view taken through a bomb constructed in accordance with an embodiment of the invention and associated with a balloon carrier, said carrier being in fragment.

Figure 2 is a transverse sectional view taken on the line 2—2 of Figure 1, and

Figure 3 is an elevational view on a reduced scale showing the bomb and its balloon carrier as herein embodied.

As disclosed in the accompanying drawing, 1 denotes an elongated cylindrical member or stick of highly combustible material, such as magnesium or a combination of magnesium and thermite. The lower end or nose portion of the member 1 at its axial center is formed to provide a relatively deep pocket 2 in which, as illustrated in Figure 1, is first placed a priming thermite charge 3 and an outer firing charge 4. These charges 3 and 4 are used when the body 1 is of magnesium. However, should the body 1 in its constituency include magnesium and thermite cast with Celluloid, charge 3 can be dispensed with.

After the charges 3 and 4 have been placed within the pocket 2, the steel nose 5 is disposed

over said end of the body 1. This nose 5 is relatively thick and has secured thereto by spot welding or otherwise, as may be preferred, at desired points therearound, extremities of the reinforcing stays 6. These stays 6, as herein disclosed, have close contact with the periphery of the body 1 and each of said stays is of a length coextensive with the combined length of the body 1 and nose 5. The end portions of the stays 6 remote from the nose 5 are held to the adjacent end portion of the body 1 by a tightly surrounding band 7.

Disposed through and carried by the central portion of the nose 5 is a detonating assembly 8 which, when the dropping bomb strikes its objective, ignites the charges within the pocket 2 with the resultant ignition of the body 1. The detonating assembly 8 may be of any structure preferred and, therefore, a detailed description and illustration thereof are believed to be unnecessary.

The body 1 adjacent to its nose end is provided with a laterally disposed vent 9 in communication with the pocket 2 and serves to relieve the gases created by the starting mixture 4. As illustrated in Figure 1, this vent is also disposed through one of the stays 6 although it is to be understood that the vent may be otherwise positioned as may be preferred.

The tail portion or that portion of the body 1 remote from the nose 5 has formed in its axial center a chamber 10 of desired dimensions and which has its walls covered with a lamination 11 of pyroxylin varnish or other acid-proof material. The upper or open portion of this chamber 10 is defined by a surrounding rabbet 12 to allow the effective mounting of a closing lid 14. This lid 14 may normally be frictionally held in place or a suitable adhesive matter used, if desired. This lid 14 is provided with a vent or opening 15 to permit the placing within the chamber 10 of a desired amount of acid solution 16. This solution may be an acetic acid solution or a nitric acid solution, although the acetic acid solution is preferred.

At substantially the axial center of the bottom of the chamber 10, the body 1 is provided with a socket 17 into which threads or is otherwise tightly engaged a timer plug 18 of a metal easily eaten by the acid solution within the chamber 10, such as magnesium alloy or the well known Dow metal which is a metallurgical standard metal. This plug 18 is provided at its lower or inserted portion with a countersink 19 of a depth to have the central portion 20 at the upper end of the plug 18 of desired thickness.

In communication with the lower portion of the socket 17 are the upper ends of the openings or ports 21. As herein disclosed, these openings or ports 21 are four in number and, as clearly indicated by dotted lines in Figure 2, these openings or ports are equidistantly spaced around the body 1. It will also be noted that these ports are disposed on an outward angle toward the nose end of the body 1 and preferably on an angle of 45 degrees, although I do not wish to be understood as limiting myself to this exact angle.

In the present embodiment of my invention, the ports or openings 21 open outwardly toward the stays 6. I do not wish to be understood as limiting myself to this exact arrangement as these openings or ports 21 may be otherwise positioned as may be deemed more expedient. These openings or ports 21 provide such drag upon the tail end of the bomb when dropping to keep the nose end down and thereby insuring proper functioning of a detonating assembly when the bomb strikes its objective.

While my improved bomb may be of all weights and may with ready modification be made into a demolition type of bomb, it is primarily intended as a light weight incendiary bomb and to be employed in connection with a balloon carrier B. This balloon carrier B is preferably inflated by hydrogen or other suitable gas and is provided with a depending neck 22 which engages over the tail end portion of the body 1 and is held thereto by an encircling band 23 or otherwise, as may be preferred.

In practice, with the acid solution 16 in the chamber 10, the balloon carrier is inflated so that it will rise to a definite altitude with a given load so that the same will have a zero lift at the desired height as established from theodolite computation on a trial balloon. After the balloon carrier B has been inflated to the computed diameter, its neck 2 is then engaged to and secured over the tail end portion of the body 1. The assembly is then turned loose and will rise to its slip stream altitude and will be carried by said slip stream until the acid solution 16 eats through the central portion of the plug 18, whereupon the gas within the balloon carrier B will escape through the vent or opening 15, chamber 10 and openings or ports 21, at which time the body 1 drops and the deflated balloon carrier B will act as an additional tail fin to keep down the nose end of the body 1. It is to be noted that the vent or opening 15, chamber 10, and an opening or port 21 constitute a passageway leading from the interior of the balloon carrier to the atmosphere. If desired, however, there may be placed within the socket 17 an igniter or pellet 24 of hexachloroethane or other material which will become effective under the action of the acid solution 16. Upon ignition of this pellet 24, the gases escaping from within the balloon carrier B will blow off

the balloon carrier B and thus provide for the desired dropping of the bomb when it reaches its calculated destination.

It has been found in practice that with the use of a 7% solution of acetic acid and with the central portion 20 of the plug 18 $\frac{3}{2}$ " thick, approximately three hours time will elapse after the release of the balloon carrier B and its carried bomb before the acid solution will eat through the portion 20 to allow for the dropping of the bomb. It is obvious, however, that by varying the strength of the acid solution 16 and/or by varying the thickness of the portion 20, or both, this time may be regulated within certain limits.

As hereinbefore stated, the body 1 can be made from magnesium with a thermite charge, but also a highly effective body can be made by casting thermite and magnesium with Celluloid in equal parts.

From the foregoing description it is thought to be obvious that an incendiary bomb constructed in accordance with my invention is particularly well adapted for use by reason of the convenience and facility with which it may be assembled and operated.

What I claim is:

1. In combination, a balloon carrier, a bomb carried thereby and having a chamber in communication with the interior of the balloon carrier, said bomb having a port leading from the chamber to the atmosphere, means for closing the opening between the chamber and the atmosphere, and an acid charge within the chamber, said closing means including a part to be eaten away under the action of the acid.

2. In combination, a balloon carrier, a bomb carried thereby and having a chamber in communication with the interior of the balloon carrier, said bomb having a port leading from the chamber to the atmosphere, means for closing the opening between the chamber and the atmosphere, an acid charge within the chamber, said closing means including a part to be eaten away under the action of the acid, an igniter

45 within the opening below the closing means, the acid charge, upon opening of said means, igniting the igniter to explode the gases escaping from within the balloon carrier.

3. In combination a balloon carrier and a bomb including a body carried by the balloon carrier, said body having a chamber in communication with the interior of the balloon carrier, a socket in the base wall of the chamber, said body having a port therethrough in communication with said socket, a plug fitted within the socket to close flow out through the port, and an acid charge within the chamber, said plug having a part to be eaten away under the action of the acid charge to open the communication between the opening and the port.

THOMAS P. DUNCAN, JR.
